UNITED STATES PATENT OFFICE

ALBERT P. BALL, OF DETROIT, MICHIGAN, ASSIGNOR TO BRIGGS MANUFACTURING COMPANY, OF DETROIT, MICHIGAN, A CORPORATION OF MICHIGAN

DOOR CONSTRUCTION

Application filed December 8, 1930. Serial No. 500,951.

This invention relates generally to vehicle door constructions, and consists of certain novel features of construction, combinations and arrangements of parts, that will be hereinafter more fully described and particularly pointed out in the appended claims.

In the accompanying drawings:

Figure 1 is a perspective view of a door embodying my invention with parts broken away;

Figure 2 is another perspective view of the door;

Figure 3 is a perspective view of the outer panel;

Figure 4 is a perspective view of the combined glass guide and header;

Figure 5 is a sectional view taken on the line 5—5 of Figure 1;

Figure 6 is a sectional view taken on the line 6—6 of Figure 1;

Figure 7 is a sectional view taken on the line 7—7 of Figure 1;

Figure 8 is a sectional view taken on the line 8—8 of Figure 1;

Figure 9 is a sectional view taken on the line 9—9 of Figure 2;

Figure 10 is a sectional view taken on the line 10—10 of Figure 2.

Referring now to the drawings, A is the inner panel; B is the outer panel; C is the sliding glass, and D is a combined glass guide and header of a door embodying my invention. As shown, the inner panel A extends from top to bottom of the door and has a flat marginal portion 1, and an inwardly depressed or offset central portion 2. The sides 3, 4, 5 and 6 respectively of the depressed portion 2 extend transversely of the door at substantially right angles to the flat marginal portion 1 and form a substantially rectangular frame, while the base 7 of the depressed portion constitutes a connecting web and is in a plane substantially parallel to the marginal portion 1. Preferably the base 7 is provided above the belt line with a window opening 9 and has inwardly projecting open return bent flanges 10, 11, 12 and 13 respectively forming a beading at the edges of said opening. This base portion 7 is also provided, preferably below the belt, with

openings 14, 15, 16, 17, 18 and 19 respectively and has inturned reinforcing flanges at the edges of said openings. As shown, the marginal portion 1 is provided above the belt with closed return bent flanges 20 and 21 respectively and is preferably offset inwardly from a point just above the belt to the lower edge of the door. The outer panel B extends upwardly from the lower edge of the inner panel to the lower edge of the window opening 9 and is provided at opposite sides of said opening with short upstanding portions 22 and 23 respectively. Preferably the outer panel B is secured against the lower offset portion 24 of the inner panel and has marginal flanges 25, 26 and 27 respectively return bent around and secured thereto. Thus the outer panel B and the outer face of the upper marginal portion 1 of the inner panel are substantially flush and form the exterior finish of the door.

In the present construction the inner panel A is reinforced and braced by a sheet 30 of metal and by the strip D that serves as a combined guide and header for the sliding glass panel. As shown, the sheet 30 is secured to the lower portion of the inner panel A, while the strip D is secured to the upper portion of said panel. Preferably the strip D is a continuous channel and is secured to the sides 3, 4 and 5 respectively of the depressed portion 2 of the panel. Any suitable resilient material such as the strip 31 may be anchored in the channel strip D to cushion the glass.

Thus from the foregoing description it will be apparent that the door is light in weight, is strong and durable and is capable of withstanding severe strains and stresses. Since the door comprises only a very few parts and the outer panel terminates at the lower edge of the window opening 9 it is also apparent that a material saving in metal has been accomplished.

What I claim as my invention is:

1. In a door, an inner panel having a portion comprising the frame of the door and having a one-piece intermediate web portion provided with a window opening, said frame being offset at substantially its upper half,

and an outer panel extending from the lower edge of the inner panel to the lower edge of the window opening therein and secured to said frame portion flush with the upper offset portion.

2. In a door, an integral inner panel stamped from a single sheet of metal having a substantially flat marginal portion a part of which is relatively offset and a central

10 portion, said central portion being provided at its upper end with a window opening, and an outer panel extending from the lower end of the inner panel to substantially the lower edge of the window opening and having

15 portions secured to the offset marginal portion aforesaid, for the purpose set forth.

3. In a door, an inner panel having a substantially flat marginal portion and an inwardly offset central portion, the central portion

20 being provided at its upper end with a window opening, and the marginal portion being provided above the lower edge of the opening with close return bent flanges and being offset below said flanges, and an outer

25 panel extending from the lower end of the inner panel to the lower edge of the window opening and secured to the offset part of the marginal portion aforesaid so that the outer

30 surfaces of said outer panel and of the marginal portion above said panel are substantially flush and constitute the exterior finish of the door.

4. In a door, an inner panel having a substantially flat marginal portion and an

35 inwardly offset central portion, the base of the offset portion being substantially parallel to the marginal portion and provided at its upper end with a window opening, said base being also provided with open return bent

40 portions forming a beading about the window opening aforesaid.

5. In a door, an inner panel having a substantially flat marginal portion and an inwardly offset central portion, the base of

45 the central portion being substantially parallel to the marginal portion and provided at its upper end with a window opening, the marginal portion being provided above the lower edge of the window opening with close

50 return bent portions being offset below said return bent portions, and an outer panel extending upwardly from the lower end of the inner panel and terminating at the lower edge of the window opening, said outer panel having

55 relatively short upstanding portions at opposite sides of the window opening and being secured to the offset part of the marginal portion aforesaid of the inner panel.

6. In a door, a stamped one-piece inner panel having a substantially flat marginal portion and an inwardly offset central portion, the central portion being provided at its upper end with a window opening, the marginal portion above the lower edge of

65 said opening being offset, and a stamped one-

piece outer panel extending from the lower edge of the inner panel to the lower edge of the window opening and secured to the marginal portion below said offset portions aforesaid so that the outer surfaces of said outer panel and of the marginal portions above said panel are substantially flush and constitute the exterior finish of the door.

In testimony whereof I affix my signature.

ALBERT P. BALL
